UNITED STATES PATENT OFFICE.

PHILIP DERROW, OF CHICAGO, ILLINOIS.

COMBINED ADVERTISING DEVICE AND MEMORANDA-HOLDER.

1,252,250.

Specification of Letters Patent.

Patented Jan. 1, 1918.

Application filed September 29, 1917. Serial No. 193,936.

To all whom it may concern:

Be it known that I, PHILIP DERROW, a citizen of the United States, residing at Chicago, in the county of Cook and State of Illinois, have invented certain new and useful Improvements in Combined Advertising Devices and Memoranda-Holders, of which the following is a specification.

This invention is primarily in the nature 10 of an advertising sign or poster having combined therewith or embodied therein a utilitarian feature in the nature of a memoranda holder or ready reference device. It is a very common practice for merchants, banks, 15 insurance companies and other business concerns to distribute gratis to their customers and the trade generally art calendars or posters on which their advertisements are more or less prominently displayed; the 20 design being that the artistic feature or characteristic of the article will prove sufficiently attractive to insure that it will be preserved and displayed instead of being thrown away or destroyed. The article of my present invention has, in its principal intended use, 25 somewhat the same nature or general character as an advertising art calendar or poster; but, instead of appealing to the purely artistic sense of the recipient, it is 30 designed to appeal rather to the practical sense by containing or embodying a utilitarian feature which gives its useful value in the home or office of the recipient. One object of the present invention is, therefore, 35 to provide an inexpensive advertising medium for gratuitous distribution which shall combine therewith a handy and convenient memoranda holder or ready reference device such, for instance, as a limited telephone 40 directory, which may be easily and quickly consulted whenever occasion may require. Another object of the invention is to provide such a memoranda holder or ready reference device as an article of manufacture 45 and sale and possessing practical utility in the home and office, irrespective of the advertising feature.

With these objects in view, the invention consists in the article hereinafter fully described, illustrated in its preferred embodiment in the accompanying drawing, and definitely pointed out in the claims. Referring to the drawing—

Figure 1 is a front elevation of the article, 55 broken off at its lower end;

Fig. 2 is a full longitudinal section on the line 2—2 of Fig. 1; and

Fig. 3 is a plan detail of one of the memorandum cards.

Referring to the drawing, 10 designates a rectangular sheet, preferably of heavy cardboard or like material, which forms the base or foundation of the device. A large rectangular opening 11 is formed centrally in this sheet, and in this opening is inserted 15 and secured a card rack which may conveniently be formed by a sheet of similar material, the marginal portions of which are bent so as to provide a front plate 12, top, bottom and side walls 13, and marginal 20 flanges 14 on said top, bottom and side walls. The walls 13 enter and snugly fit the rectangular opening 11, and the flanges 14 are adhered to the rear side of the base 10. The front wall 13 of the rack is formed with a 25 series of parallel horizontal slots 15 extending the full width thereof, and a sheet 16 of heavy paper, cardboard, or the like, covers the opening 11 and the flanges 14 on the rear side of the base 10 and at its marginal 30 portions is adhered to the latter, as clearly shown in Fig. 2. The construction described provides a pocket for receiving a series of cards, one of which is shown in detail in Fig. 3. Each of these cards comprises a 35 body portion 17 and a head portion 18 of somewhat greater width than the body portion, thereby providing shoulders 19 which limit the extent to which the card may be entered into the pocket through one of the 40 slots 15. When the cards are all fitted to the rack, the body portions 17 lie wholly within the pocket, as clearly shown in Fig. 2, while the head portions 18 project above the several slots in parallel and slightly overlapping order, being visible from the front of the device, as clearly shown in Fig. 1. The body portions 17 of the cards are 45 designed to carry memoranda of any useful character, such, for instance, as telephone 50 directory memoranda indicated at 20 in Fig. 3; such memoranda being preferably arranged alphabetically on the several cards, and each card being provided on the ends of the exposed head portion with appropriate alphabetical indexes indicated at 21. It will be observed that by reason of the location of the body portions of the cards wholly 55 within the pocket of the rack, such body portions are protected from becoming soiled 60

or injured in any way. Preferably, and as herein shown, a calendar pad, indicated at 22, is attached to the lower portion of the front wall 12 of the rack, but this feature 5 is optional and immaterial to the present invention.

Where the article is designed to serve as an advertising medium, in which character I contemplate it will find its chief utility, 10 the base 10 affords ample space at the top, above the card rack, for printing thereon the name and business of the advertiser, as indicated at 23 in Fig. 1; while the exposed heads 18 of the several cards afford convenient 15 space for the announcement of the line of goods carried by the advertiser, as indicated at 24. Additional advertising matter of any desirable character may, of course, be carried on the sides of the base 10; which 20 provide ample space therefor.

It is believed that the character, structure and utility of the invention will be readily apparent from the foregoing description. It is manifest that the structural details may 25 be considerably modified without departing from the substance of the invention or sacrificing any of the advantages thereof. Hence, I do not limit the invention to the exact structure shown and described, except 30 to the extent clearly indicated in specific claims.

I claim:

1. In a device of the character described, the combination with a flat base plate, of a 35 one-piece rectangular card rack of less length and width than said base plate, said card rack comprising a front wall formed with a series of parallel transverse slots, narrow side and end walls, and flanges on said 40 side and end walls lying in a plane parallel with said front wall and secured to said base plate, and a series of memoranda cards hav-

ing body portions adapted to pass through said slots and head portions of greater width than said body portions adapted to project 45 in stepped relation above said slots, substantially as described.

2. In a device of the character described, the combination with a flat base plate formed with a substantially central rectangular opening, of a one-piece card rack comprising a front wall having a series of parallel transverse slots, narrow side and end walls passing through and fitting the edges of said opening, and flanges on said 50 side and end walls secured to the rear side of said base plate around said opening, and a series of memoranda cards having body portions adapted to pass through said slots and head portions of greater width than 55 said body portions adapted to project in stepped relation above said slots, substantially as described.

3. In a device of the character described, the combination with a flat cardboard base 65 formed with a substantially central rectangular opening, of a card rack pressed to shape from a single cardboard blank and comprising a front wall having a series of parallel transverse slots, narrow side and end walls passing through and fitting the edges of said opening, and flanges on said 70 side and end walls secured to the rear side of said base plate around said opening, a covering sheet overlying said opening on the 75 rear side of said base, and a series of memoranda cards having body portions adapted to pass through said slots and head portions of greater width than said body portions adapted to project in stepped relation above 80 said slots, said head portions carrying alphabetical indexes of the contents of said cards substantially as described.

PHILIP DERROW.
